UNITED STATES PATENT OFFICE

137,646

DESIGN FOR AN EXERCISING APPARATUS

Orville Stamm, Chicago, Ill.

Application August 18, 1943, Serial No. 110,938

Term of patent 14 years

(Cl. D34—5)

To all whom it may concern:

Be it known that I, Orville Stamm, a citizen of the United States, residing at 2815 Orchard St., in the city of Chicago, in the county of Cook and State of Illinois, have invented a new, original, and ornamental Design for Exercising Apparatus, of which the following is a specification, reference being had to the accompanying drawing, forming a part thereof.

The figure is a perspective view of an exercising apparatus, showing my new design.

I claim:

The ornamental design for an exercising apparatus, substantially as shown.

ORVILLE STAMM.
